UNITED STATES PATENT OFFICE

WALTER R. KNEELAND, OF PITTSBURGH, PENNSYLVANIA

ROLLING MILL

Application filed March 17, 1927. Serial No. 176,082.

My invention relates to improvements in the structure of hot-mills; that is to say, mills in which light steel plates and steel sheets are rolled. It is not limited to mills for the rolling of steel, but it finds practical application in that industry, and so applied I shall show and describe it. The object of invention is the mechanical handling of the material in course of the rolling operation. I employ the apparatus of this application in a mill equipped for the control during the rolling operation of the temperature of the bodies of the rolls, and so employing it I am able to roll sheets in larger sizes and in greater quantities and of better uniformity, with saving of time, and in so doing to effect substantial economies. The matter of the control of the temperature of the roll bodies to which I here allude is the subject of a companion application for Letters Patent, filed by me March 17, 1927, Serial No. 176,081.

In the accompanying drawings Figs. I and II are views in elevation and in plan of a hot-mill in which my present invention is embodied. Fig. Ia illustrates in alternative form a detail of the assembly as seen in Fig. I. Fig. III is a view to larger scale, illustrating in fragmentary manner a certain screen which may advantageously be employed as an accessory to the feed tables shown in Figs. I and II. Fig. IV is a fragmentary view, showing in side elevation the rolls and their driving apparatus. From the showing of Fig. IV the feed tables are removed. Fig. V is a view corresponding to Fig. I and illustrating a mill of another type, having applied to it the feed table structure of the present invention.

Referring first to Figs. I-III, the mill shown is a three-high mill. It is served by tables, one on each side. Each table is compound, and consists of an outer swinging member 3 and an inner stationary member; and in this case of a three-high mill there is a stationary member on each side for each roll-pass, and these upper and lower stationary members are designated 5 and 6. The stationary members 5 above are upwardly inclined to the upper roll pass and are adapted to convey material to and from the roll pass;

the stationary members 6 below are downwardly inclined to the lower roll pass and they too are adapted to carry material to and from the roll pass. The outer swinging members 3 may be brought to positions of alignment alternately with the upper members 5 or the lower members 6. Fig. I shows them in full lines in alignment with members 5 and it shows in dotted lines the proximate portion of member 3 on the left in alignment with its companion lower member 6.

Considering first the minute structure of the table members 3, they will be seen to be made up of lines of idly turning disks 30 (cf. Fig. II). Disks are employed rather than rollers in order to reduce to a minimum the extent of supporting contact with the material under treatment and accordingly to reduce to a minimum escape of heat. The disks may be from an inch and one-eighth to an inch and one-quarter wide and may be spaced widely apart, as Fig. II shows. To the same end, the retention of heat, screens 31 of suitable material, asbestos composition, for example, may extend above and below the path of advance of the material upon the table members 3 (cf. Fig. III); and, in order to keep the axles of the disks cool and yet to bring the screens as near as possible to the surfaces of the material, the screens may be of the undulating shape shown in Fig. III. The screens are slotted for the passage through them of the bodies of the disks. The disks of the successive lines stand in staggered succession, as also appears in Fig. II. Certain of the axles 32 of the disks 30 carry sprocket wheels 33 which turn idly upon them, and over these sprocket wheels positively driven continuous chains 34 are trained. These chains it will be understood are equipped with means for engaging the material under treatment, and additional means are provided (though not shown) for driving the chains alternately in one direction or the other, to convey along the table the material under treatment.

In Fig. I the table members 3 are shown to consist each of two sets or decks of disks. The upper set of disks may or may not engage from above the material when borne by the lower set of disks. The table members

3 are in this case pivoted for swinging on transverse axes, to come to alignment alternately with one or the other of the adjacent table members 5 and 6. The table member 3 on the left for example may swing 5 clockwise from the full-line to the dotted-line position indicated, or it may swing counter-clockwise through the complementary arc, and come to the same relative position; but it will be remarked that in the 10 latter case the table member is reversed and turned end for end and the set of disks which had been the upper becomes the lower. More minute details in range of swing will be explained below.

15 Table members 5 and 6, like the table members 3, consist essentially of idly turning material-sustaining disks, and they too are equipped with material driving sprocket chains. Table member 5 on the left (on the 20 intake side of the upper pass), at its outer end is preferably provided with a device for removing bars from the bottom of a pile brought to the position indicated at B, Fig. I, and for bringing them singly to position 25 on table members 5 where they will be engaged by the sprocket chains 54 with which the table member 5 is equipped. Such a device is found in the positively driven endless belts 55 equipped with dogs 56. Table member 6 on the left (on the delivery side of the 30 lower pass) at its outer end is in Fig. I shown to be provided with a positively driven roller 67 underlying the pathway in which the material advances, and with cooperating 35 and idly turning pressure and guide rollers or disks 68 and 69. Roller 67 is faced with suitable porous material, such as asbestos fibre, and means are provided, such as a tank 7 and a feed roller 70 for filling the asbestos face of roller 67 with charcoal wash or equivalent adhesion preventing material, to be applied to the nether surface of the 40 passing sheet.

45 Alternative means of applying to the nether surface of an advancing sheet an adhesion preventing coating of carbon are shown in Fig. Ia. In place of the roll-67 of Fig. I burners 77 are arranged to project their 50 flames upon the sheet as it advances between the guiding disks 69, and the flame so projected may, as will be recognized, be such as to afford the desired smoking, that is to say the desired deposit of carbon. The fuel may 55 for instance be acetylene and conditions of combustion suitable to gain the end in view may be established.

The progress of material through the mill 60 may be followed with Fig. I in view. As there illustrated the direction of rolling is from left to right through the upper pass and from right to left through the lower.

65 One, two, three or more bars, depending on size and gauge, are taken from the bar heating furnace, scaled, and deposited in

a pile B in cradle 8. Cradle 8 so loaded is brought to the position relative to the table member 5 to the left, which is shown in Fig. I. The dogs 56 which the chains 55 carry, with each revolution kick out the bottom bar of 70 the pile and so in repeated revolutions deliver the bars in properly spaced succession to the chains 54 which carry them to the upper roll pass.

75 Passing through the mill, the articles emerge on the right, and are received first by the stationary table member 5 on the right and then by the lower deck of disks of swinging table member 3. When all the articles which make up a single run have been received by table member 3 on the right, a switch is shifted, the driving chains of table member 3 on the right stop, and table member 3 swings counter-clockwise from the position shown of alignment with table member 5 above to alignment with table member 6 below. At this point the table-swinging operation is arrested, the table member 3 is locked, and the travel of the chains 34 is renewed, but in reverse direction. The 80 articles then travel from table member 3, across the stationary table member 6, and enter the lower roll pass.

85 Passing a second time through the mill, the articles cross table member 6 on the left and enter table member 3 on the left whose lower deck of disks then is aligned with table member 6. Table member 3, having received the articles which make up the single run, rises automatically in counter-clockwise turning to the full-line position shown 90 in Fig. I, of alignment with upper table member 5 on the left. Reversal in the direction of travel of the chains 34 of table member 3 will cause the articles to advance 95 to table member 5 again. The cycle of operations then completed is repeated, up to the point where the articles emerge a second time from the lower roll pass. At this point 100 the table member 3 on the left is swung 105 further in clockwise turning than before, until its upper deck of disks 30 comes to alignment with the disks of table member 6. This 110 is the position of table 3 which in Fig. I is indicated in dotted lines. The chains 34 115 of this upper series of disks being then at rest, the articles after passing over roller 67 and after receiving from roller 67 on their under surfaces a charcoal wash, are automatically piled in the position indicated at 120 C, Fig. I.

125 When the table member 3 has thus received all of the run, it is swung counter-clockwise until its upper deck comes to alignment with table member 5 on the left. The packs then are rolled in like manner as the single articles previously had been. The packs pass twice through the mill. When they emerge from the lower roll pass they are received upon the lower deck of the table member 3 130

on the left. The table member 3 swings to the full-line position of Fig. I, and then by the travel of its chains 34 in proper direction the table member 3 delivers the rolled packs to the doubler 80, shown to the left. The roughing and matching passes have now been completed in continuous run. The doubler forms no part of my present invention, and I do not here describe it in detail. The 10 doubled packs go to a heating furnace.

When all the bars in a heat have been worked to the form of doubled packs, and when the fours and the finishing passes are to be rolled, the roller throws a switch, and a new set of operating circuits is brought into play. The packs are brought from the heating furnace and placed one by one on the lower deck of table member 3 on the left. Each pack advances through the mill as before, until it is received on the lower deck of table member 3 on the right. This table then swings in opposite and clockwise turning and through a complementary arc until the ends of the table member are reversed 25 and the deck which had been the upper but which now is the lower comes to alignment with table member 6 on the right. The material now rests on the deck last mentioned.

The travel of the chains 34 with which the pack-supporting set of disks is equipped carries the pack to the left, from table member 3 to table member 6. Thence it advances to and through the lower roll pass. Passing through the mill the pack is re-received on 35 the lower deck of table member 3 on the left and is by it carried again to the doubler. The doubled and sheared pack is placed again on table member 3. The pack may then consist of as many as twenty sheets. It is borne by table members 3 and 5 to the upper roll pass, it passes through and is received by table member 3 on the right. This table member swings clockwise again and delivers the pack to the table member 6 which in turn 40 carries it to the lower roll pass. Advancing again through the mill, the pack is received again on the lower deck of table member 3 on the left, and this table now also swings clockwise, inverting, shifting the support of 45 the material to the deck of disks previously above but now brought to position beneath. Upon this set of disks the pack is advanced again to table member 5 and to the upper roll pass.

The rolling operation may with this pass be completed, and in that case the pack passes out from the right hand end of table member 3 on the right. But if further rolling be required, the pack may be passed twice more 50 through the mill. If four passes suffice, the screw pressure on the rolls may, after the fourth pass, be relieved, and the finished pack may pass through the upper roll pass for the last time without the exertion of any rolling 55 pressure; or, by way of alternative, after

the third pass the pressure may be so far relieved that the reduction still to be effected may be accomplished in two steps, in the fourth and fifth passes. In such manner the rolling pressure may be distributed so as to 70 finish in three, five, or seven passes, as may be preferred.

In further general comment I would remark that throughout the finishing operation the packs passing through the mill have 75 been received between the two decks of disks and between the screens 31; they have not come into contact with large bodies of metal, excepting only the rolls of the mill. In consequence, they have been finished with less loss 80 of temperature than is usual. The pack has been reheated but once, and the fours and the finishing passes have been rolled in continuity, without any intervening heating.

The material may enter the mill as a single 85 large slab, rather than as a succession of bars. The slab would be advanced to the mill resting from above on the upper series of disks 30, and the material would be received again from the mill on the lower series of 90 disks. After the fourth pass the piece would be run out to the rear of the table and sheared, say to five pieces. These would be coated, run together, piled, and placed again on the upper series of disks 30 of the table 95 member 3 on the left and by the upper disks the so made pack would be advanced to the mill. It would be well to give to the pack four matching passes, with relatively light pressure. In consequence, the opening of the 100 pack will be easier. A second slab might under such conditions of operation be entered at the upper pass while the first was being run off the rear end of table 3 at the left to be sheared. And the second slab would receive 105 its roughing passes while the first was being sheared. Then while the second slab was run off to be sheared, the first piece of material, now made into a pack, would in the upper pass receive its first matching pass. This the 110 first piece of material would then receive its matching passes while the second was being sheared and made into a pack. While the mill in the lower pass was giving to the second pack its last matching pass a third 115 slab might be placed in position and enter the mill for its first roughing pass as the second pack was run off the rear of the table 3 at the left to be doubled.

The mill shown in Fig. I is a three-high 120 mill. The middle roll may be understood to be carried in housings which are vertically immovable, and it may be understood that the top and bottom rolls, mounted in counterpoise, are simultaneously adjustable by an electrically driven screw-down, toward and from the middle roll. All three of the rolls are positively driven at equal surface speeds. As hot-rolling now is practiced the top roll, 130

mounted to turn in response to the pull of the material, travels at a speed about 94% of that of the bottom roll. This drag of the top roll causes each sheet in the pack to move 5 slightly, relatively to the sheet which contacts with it. In consequence fine slivers are produced, torn by the so moving sheets one from the other, and these slivers are to a slight extent embedded in the surface of the companion sheet. The tearing of the sheets apart is thus rendered more difficult, the sheets are marred, and the waste is great. By driving both of the cooperating pair of rolls at equal 10 surface speeds slivering is not created, there is no such interpenetration between sheets, intermediate opening of the pack is unnecessary, and the ultimate opening is accomplished without difficulty. In consequence of 15 positive drive of both of the pair of cooperating rolls the pack may be carried through the mill in more precise course, and this makes for expedition, particularly in rolling long 20 packs.

Referring particularly to Fig. IV, all three 25 of the rolls 1 are seen to be positively driven from a three-high pinion stand 9. This stand of pinions can be slid away from the mill, carrying with it the connecting spindles 90 and coupling boxes 91. The pinion stand unit 30 includes three housings 92, the pinions themselves, bearing the numeral 9, the spindles 90, and the coupling boxes 91. This unit may by well-known means be backed away from the mill, the mill may then be lifted out and replaced, and the pinion stand may then be advanced again to make engagement with the 35 newly placed mill. A change of mill may thus be made with great expedition and the newly placed mill may be set up, ready for 40 operation, with its rolls already heated for service.

The stationary table members 5 and 6 may conveniently be borne by the mill housings 2 and with each replacement the new mill 45 stand may be equipped with these stationary table members.

I have shown and described my invention in application to a three-high mill with two 50 passes. In Fig. V I indicate its applicability to a mill of other type, and specifically to a two-high mill. In this case the table on the delivery side of the mill, the table on the right as the drawing shows it, is made up of two members,—the stationary member 5 and the 55 swinging member 37. The swinging table member 37 on the right is equipped with a single deck of disks. The movement of this table member is not a simple swing on fixed trunnions, but a swing along lines *a* and *b* 60 from the full-line to the dotted-line position. And in the dotted-line position it will be observed that this table sustaining the material 65 delivers it above the rolls and on the intake side of the mill, and to the table member on 70 the left swing to alignment with it.

I claim as my invention:

1. In combination with a rolling mill including a plurality of roll passes in a single roll stand, a swinging conveyor table including two decks arranged adjacent to the roll stand and adapted to be swung from a position of alignment with one roll pass to one or another of two positions in which its two decks severally are in alignment with the other roll pass. 75

2. The combination of claim 1, the conveyor table being composed of rotatable work-sustaining elements, together with means for rotating the work-sustaining elements alternately in either direction. 80

3. In combination with a rolling mill, including a plurality of roll passes arranged in a single roll stand, a conveyor table including two decks of rotatable work-sustaining members adapted to be swung from a position in which it stands in alignment with one roll pass, to either of two alternate positions in which its two decks severally are in alignment with the other roll pass, the said table being further adapted to be swung through the complementary arc of a complete rotation, whereby material resting by gravity upon what had been the lower deck, but which by such swinging becomes the upper deck, is caused to rest by gravity upon the deck which had been the upper deck, but which by such swinging has become the lower deck. 95

4. In combination with a rolling mill, a swinging conveyor table including two work-sustaining decks of idly turning disks arranged in superposed relative positions, the table in its range of swinging adapted to be brought to positions in which the two decks alternately co-operate with the mill, and heat-insulating screens extending transversely of each set of disks. 100

5. In a rolling mill and in combination with a roll stand, a feed table consisting of a succession of material-carrying rollers and a heat insulating screen extending adjacent 110 the pathway of the material on the rollers.

6. In a rolling mill and in combination with a roll stand, a feed table consisting of a succession of series of disks and a slotted heat insulating screen extending adjacent the 115 pathway of material upon such disks through the slots of which the disks extend.

7. In a rolling mill and in combination with a roll stand, a feed table consisting of a succession of series of disks mounted on axes, and a slotted and undulating heat insulating screen extending adjacent the pathway of material upon such disks, the axles of the disks being arranged externally of the screen, and the disks extending through the slots in 120 the screen. 125

In testimony whereof I have hereunto set my hand.
